HYDRAULIC METHOD OF CARRYING THE DOWN-THRUST OF A DEEP-WELL TURBINE PUMP

Application filed February 29, 1928. Serial No. 257,905.

My invention relates to turbine well pumps and has as a general object the improvement of these pumps, so that they may be successfully used in pumping wells of great depth without certain disadvantages which are encountered when the ordinary pump is used.

A common form of turbine pump includes a pump head mounted over the upper end of a well, a column pipe provided on the pump head and extending into the well to a depth of several hundred feet, and a pump or impeller section attached to the lower end of the column pipe. Rotatably suspended from the pump head and extending down through the column pipe to the pump section is a line shaft. Rotatably mounted in the pump section and supported upon the lower end of the line shaft is a rotor having a series of impellers. Means are provided upon the pump head for rotating the line shaft and the rotor so as to raise a column of liquid upward through the column pipe. The line shaft is usually surrounded by a shaft tubing which carries line shaft bearings which are disposed at intervals throughout its length. While very successful in pumping wells only a few hundred feet in depth, the type of pump above described has certain weaknesses which hitherto have prevented its general use in pumping the deeper wells. The latter include the major portion of all oil wells which usually range from one to five thousand feet in depth.

Of the above mentioned weaknesses, the most difficult to overcome has resulted from the stretching of the line shaft because of its own weight or the additional load of the column of liquid forced upward by the rotor, which, as previously mentioned, is secured to the line shaft. This stretching causes the impellers on the rotor to wear against the lower walls of the impeller chambers which greatly impairs the efficiency of the pump if it does not render it entirely inoperative.

It is, therefore, an object of my invention to provide a deep-well turbine pump in which stretch in the line shaft is compensated for so as not to destroy the proper positioning of the impellers in the impeller chambers.

Line shafts of turbine pumps installed in

the deeper wells must be rotated at a speed of about 4000 R. P. M. and as the line shaft bearings cannot be economically placed any closer than at intervals of five feet apart in the shaft tubing, it is absolutely essential that a considerable portion of the weight of the column of pumped liquid be carried by the line shaft in order to keep it stretched taut like a plumb line, thus preventing vibration or whipping of the inter-bearing sections of the line shaft near its lower end, especially where small shafting is used.

It is accordingly another object of my invention to provide a deep-well turbine pump in which stretch in the line shaft is compensated for, while at the same time a portion of the weight of the pumped column of liquid is supported by the line shaft.

Previous devices have aimed to compensate for this stretching of the line shaft, but all of these required a seal to be maintained between members which rotated relative to each other in the bottom of the well. The sand present in practically all wells soon worked in between these members and destroyed the seal, thus causing these devices to fail.

It is a further object of my invention to provide in a deep-well turbine pump, a device for compensating for stretch in the line shaft, this device being relatively insusceptible to wearing action of the sand in the well.

Further objects and advantages will be made manifest in the following description and in the accompanying drawings, in which—

Fig. 1 is a diagrammatic view illustrating the installation of a turbine pump embodying my invention.

Figs. 2 and 3 are vertical medial sectional views of a portion of the pumps shown in Fig. 1, illustrating in detail the features of my invention.

Fig. 4 is a fragmentary detailed view illustrating certain parts of the invention shown in Fig. 2 in different positions relative to each other.

Figs. 5, 6, and 7 are horizontal sectional views taken on the correspondingly numbered lines of Fig. 2.

Referring specifically to the drawings, the

numeral 10 indicates a deep-well turbine pump inserted in a well 11 having an outer casing 12. The pump 10 includes a pump head 13 from which a column pipe 14 extends 5 downward through the well to a point below the level of the liquid in the well. The lower end of the column pipe 14 is threaded and screws into the upper end of a main bearing casting 15. Connected together as by cap 10 screws 16 is a series of pump bowl castings 17 which form a pump section 18 and which is connected to the lower end of the main bearing casting 15 as by cap screws 20. Secured upon the lower end of the lowermost pump 15 bowl casting 17 by cap screws 21 is a tubular bearing housing 22, from the lower end of which extends a fluid inlet pipe 23.

Formed in the lower end of each of the pump bowl castings is an impeller chamber 20 25 which is connected by channels 26 to the impeller chamber of the pump bowl immediately thereabove. Formed centrally in each of the castings 17 is a bearing 27.

The bearing housing 22 has a bearing sleeve 25 28 formed centrally therein about which vertical openings 29 extend upward through the housing. The sleeve 28 provides a radial bearing 30 throughout its length and a plug 31 secured into the lower end of the sleeve 28 30 supports a thrust bearing 33 in its lower end.

The pump section 18 is provided with a rotor 35 which includes a pump shaft 36 extending vertically through the bearings 27 and 30 and having a position of rest upon the 35 thrust bearing 33. Keyed upon the pump shaft 36 so as to be uniformly positioned in the impeller chambers 25 of the pump section 18 are impellers 38.

The main bearing casting 15 is tubular in 40 form and includes an outer shell 40, and an inner shell 41 which is supported thereon by webs 42 to form vertical passages 43 around the inner shell 41 between the lower and upper ends of the bearing casting 15. Formed 45 in the lower end of the casting 15 is a pumped fluid passage 44 which connects the uppermost impeller bowl 17 with the vertical passages 43.

Formed within the inner shell 41 is a cylindrical chamber 45 which is connected with the exterior of the main casting 15 by ports 46 which are formed through the webs 42. Threadedly received in the lower end of the inner shell 41 is a main bearing sleeve 48 50 which has a central bore in which is pressed a main bearing bushing 49.

The pump shaft 36 extends upward from the uppermost pump bowl casting 17 through the main bearing bushing 49 and into the chamber 45 so as to terminate near the upper end thereof. The upper end of the pump shaft 60 65 36 is provided with splines 50 for a purpose to be described later.

Formed about the upper end of the shaft 36 in the chamber 45 is a piston and cylinder

mechanism 52 of my invention. This mechanism includes a valve ring or collar 53 which is tightly fitted upon the shaft 36 directly above the uppermost pump bowl 17 and is secured thereto against longitudinal displacement by any suitable means as by a pin 54.

Also disposed about the shaft 36 so as to have a snug bearing fit in the bushing 49 is a piston sleeve 56. This sleeve terminates at 75 its lower end opposite the lower end of the bushing 49 and is secured to the shaft 36 as by pins 57. The central portion of the sleeve 56 is counterbored out to provide an annular chamber 60 disposed about the shaft 36. Formed in the inner surface of the sleeve between the lower end of the chamber 60 and the lower end of the sleeve are a number of vertical channels 61 which communicate between the passage 44 and the lower end of the 80 chamber 60. The upper end of the chamber 60 terminates a slight distance below the upper end of the piston sleeve 56, and openings 62 are provided in the sleeve to communicate between the upper end of the chamber 60 and the outside of the sleeve. Formed upon the upper end of the sleeve 56 is a piston or head 65 having a packing 66 which is preferably formed of lead and which is maintained under pressure by a follower nut 67 screwed 85 upon the threaded upper end of the sleeve 56, and forcing the packing 66 against an annular shoulder 68 formed on the sleeve 56. The piston sleeve 49 and the piston 65 form a 90 piston structure 69.

Disposed in the upper end of the chamber 45 and extending downward over the upper end of the shaft 36 is a steel drive sleeve 70, the interior space of which is divided by a wall 71 into a threaded upper shaft pocket 72 and a lower key pocket 73. The key pocket 73 is provided with vertical keys which fit slidably into the splines 50 formed in the outer surface of the shaft 36. The lower end of the drive sleeve 70 is slightly enlarged and extends into the upper end of a cylinder sleeve 75 which is securely retained on the drive sleeve 70 as by headless screws 76. The cylinder sleeve 75 extends downward over the piston 65 so that the packing 66 makes a fluid-tight fit with the inner surface thereof. Provided in the sleeve 75 just below the lower end of the drive sleeve 70 is an exhaust port 78.

Formed inwardly on the lower end of the cylinder sleeve 75 is a cylinder head 79 which has an annular packing 80 preferably formed of lead and forced into tight engagement with the outer surface of the piston sleeve 56 by compression between a follower 81 which is screwed into the internally threaded lower end of the cylinder sleeve 75, and an annular shoulder 83 projecting inwardly from the sleeve 75. The cylinder sleeve 75 and the cylinder head 79 cooperate to form a cylinder

structure 84 which cooperates with the piston structure 69 to define a chamber 85, the volume of which varies as the rotor 35 moves up and down. This chamber communicates through the port 62, the chamber 60, and the channels 61 with the space 44 within the lower end of the main bearing casting 15. The cylinder sleeve 75 has such an outer diameter that a space 90 is formed between this sleeve and the inner sleeve 41, which space communicates between the port 78 and the ports 46.

The upper end of the inner shell 41 is provided with an internally threaded neck 92 which is adapted to receive the lower end of a line shaft tubing 93 which extends upward to the pump head 13 from which it is supported. The interior of this tubing is in communication with the space 90. Disposed at intervals throughout the length of the tube 93 are line shaft bearings, not shown. Supported by the pump head 13 and adapted to be rotated thereby is a line shaft 95 which extends downward through the line shaft bearings provided in the shaft tubing 93, the lower end of the line shaft 95 being screwed into the threaded pocket 72 in the upper end of the steel drive sleeve 70.

The operation of my invention is as follows:

The pump section 18 is adapted to be disposed at considerable depth in the well 12, this depth varying from 500 to 3000 feet or more. In order to pump from this depth it is necessary that the rotor 35 be rotated at a very high rate, this usually being about 4000 R. P. M. In order to prevent the line shaft 95 from whipping, it is necessary that a considerable weight be placed upon the lower end of this shaft. Owing to the stretch in this line shaft in a deep-well however, it has been impossible to follow the usual custom of installations in the shallower wells, of suspending the rotor 35 directly upon the lower end of the line shaft 95. If this were done in the deep wells, the stretch in the line shaft would cause the impellers 38 of the rotor to drag against the lower walls of the impeller chambers 25. The proper positions for operating the rotor 35 is the broken line position 100, as clearly shown in Fig. 2. When the rotor 35 is thus disposed, the lower end of the shaft 36 is raised slightly, as shown by broken lines 101 in Fig. 3. The placing of a weight upon the lower end of the line shaft and the maintaining of the rotor 35 in the position of broken lines 100 during the pumping operation is accomplished as follows:

When the pump 10 is started, the shaft 36 rests downward against the thrust bearing 33, as it is shown in full lines in Figs. 2 and 3. The line shaft 95 is then adjusted at the top of the ground so that the slack is removed therefrom and the cylinder head 79 is raised from the main bearing sleeve 48, but not far enough to contact the annular shoulder 68.

In a deep well this may best be accomplished by the use of certain indicating devices disclosed in my co-pending applications, such as Ser. No. 133,879, filed September 7, 1926. The line shaft 95 is now rotated at the proper speed by the pump head 13 which causes the impellers 38 to throw a stream of water upward through the space 44 at an exceedingly high pressure so that a column of water is raised throughout the length of the column pipe 14 and discharged from the pump head 13. As the pumping action of the rotor 35 builds up this high pressure in the space 44, a portion of the pumped fluid flows upward through the channels 61, the chamber 60 and the port 62 into the chamber 85. This exerts a force against the piston head 65 and the cylinder head 79, tending to separate these and suspend the pump rotor 35 upon the lower end of the line shaft 95. This raises the rotor 35 to its broken line position which brings an upper face 105 of the valve ring 53 into tight sliding fit with the lower end of the bearing sleeve 49, as shown in Fig. 4. This effectively shuts off a flow of pumped liquid into the lower end of the channel 61 so as to stop a supply of this liquid to the chamber 85. The lifting pressure of the liquid in the chamber 85 is thus automatically limited so that this lifting force will not be excessive, for as soon as the valve ring 53 comes in contact with the lower end of the main bearing sleeve 49, the normal slight leakage from the chamber 85 past the packers 66 and 80 will decrease the pressure in this chamber and permit the rotor 35 to drop a slight distance so that the valve ring 53 will move out of contact with the main bearing bushing 49.

Thus, it is seen that by my invention the rotor 35 is not only maintained in position for securing absolutely the best pumping results, but downward tension is constantly imposed upon the lower end of the line shaft 95 so that whipping of the sections of this shaft between adjacent line shaft bearings is effectively prevented.

Attention is also directed to the fact that excepting for the slight vertical movement of the piston 65 in the cylinder 75 which occurs when the rotor 35 moves between its broken line and full line positions, the piston 65 and the cylinder 75 rotate as a single unit. The wear between these members is thus negligible, giving the piston and cylinder mechanism 52 of my pump almost unlimited life.

As the adjustment effected by this mechanism insures the line shaft and the rotor operating with a minimum of wear, the entire pump 10 will have a much longer useful life than any other deep-well turbine pump previously produced.

I claim as my invention:

1. In a deep-well turbine pump, the combination of: a pump head; a pump section hav-

ing a pump shaft; an impeller mounted on said pump shaft in said pump section; a line shaft adapted to be rotated by said pump head; means for drivably connecting said 5 pump shaft and said line shaft in a manner to permit relative axial movement therebetween, so that said impeller may be rotated by said line shaft to set up a fluid pressure; and means for utilizing said fluid pressure to 10 pull downwardly on said line shaft.

2. In a deep-well pump, the combination of: a pump section; a rotor in said pump section, said rotor including a pump shaft; a line shaft drivably connected to said pump 15 shaft; and means co-acting with both said line shaft and said pump shaft for utilizing the fluid pressure developed by said pump section to urge said line shaft and said pump shaft toward each other.

20 3. In a deep-well pump, the combination of: a pump section; a rotor in said pump section, said rotor including a pump shaft; a line shaft; a piston-and-cylinder mechanism joining said line shaft and said pump shaft, said 25 mechanism providing a chamber in communication with the fluid pumped by said pump section; and means for driving said line shaft.

4. In a deep-well pump, the combination of: a pump section; a rotor in said pump section, said rotor including a pump shaft; a line shaft drivably connected to said pump shaft; a cylinder structure secured to one of 30 said shafts; a piston structure slidable in said cylinder structure and secured to the 35 other of said shafts; and means for supplying fluid under pressure to said cylinder structure in a manner to act on said piston structure.

5. In a deep-well pump, the combination 40 of: a pump section; a rotor in said pump section, said rotor including a pump shaft; a line shaft drivably connected to said pump shaft; a cylinder structure secured to said line shaft; and a piston structure slidable in 45 said cylinder structure and secured to said pump shaft, there being an opening through said piston structure through which fluid pressure developed by said pump section may be transmitted to said cylinder structure in 50 a manner tending to draw said shafts together.

6. In a deep-well pump, the combination 55 of: a pump section; a rotor in said pump section, said rotor including a pump shaft; a line shaft drivably connected to said pump shaft; means co-acting with both said line shaft and said pump shaft for utilizing the fluid pressure developed by said pump section to urge said line shaft and said pump 60 shaft toward each other; and means controlled by the position of said pump shaft for controlling the amount of said fluid pressure supplied to said first-named means.

7. In a deep-well pump, the combination 65 of: a pump section; a rotor in said pump sec-

tion, said rotor including a pump shaft; a line shaft drivably connected to said pump shaft; a cylinder structure secured to one of said shafts; a piston structure slidable in said cylinder structure and secured to the other of said shafts; means for supplying fluid under pressure to said cylinder structure in a manner to act on said piston structure; and valve means controlled by the position of 70 said pump shaft and cooperating with said piston structure to control the amount of fluid pressure supplied to said cylinder structure. 75

8. A combination as defined in claim 4 in which a small leakage from said cylinder structure takes place, and including means for replacing the fluid leaking from said cylinder structure, said means supplying fluid in amount determined by the position of 80 said pump shaft. 85

9. A combination as defined in claim 4 including a bearing means for journalling said piston structure relative to said pump section.

10. In a deep-well pump, the combination 90 of: a pump section; a rotor in said pump section, said rotor including a pump shaft; a line shaft drivably connected to said pump shaft; a primary sleeve extending downward from said line shaft and rotatable therewith; a secondary sleeve extending upward from 95 said pump shaft and telescoping with said primary sleeve; a head on said primary sleeve in sliding engagement with said secondary sleeve; a head on said secondary sleeve in 100 sliding engagement with said primary sleeve, said sleeves and said heads defining a chamber; and means for supplying a fluid to said chamber. 105

11. In a deep-well pump, the combination 105 of: a pump section; a rotor in said pump section, said rotor including a pump shaft; a line shaft drivably connected to said pump shaft; a primary sleeve extending downward from said line shaft and rotatable therewith; a secondary sleeve extending upward from 110 said pump shaft and telescoping with said primary sleeve; a head on said primary sleeve in sliding engagement with said secondary sleeve; a head on said secondary sleeve in 115 sliding engagement with said primary sleeve, said sleeves and said heads defining a chamber, said chamber being in communication with the fluid being pumped by said pump section; and valve means controlled by the 120 position of said pump shaft for controlling the amount of flow to said chamber. 125

12. In a deep-well pump, the combination 125 of: a pump section; a rotor in said pump section, said rotor including a pump shaft; a line shaft; a drive sleeve secured to said line shaft and in which said pump shaft is axially movable; a primary sleeve secured to said drive sleeve; a secondary sleeve extending upward from said pump shaft and tele- 130

scoping with said primary sleeve; a head on said primary sleeve in sliding engagement with said secondary sleeve; a head on said secondary sleeve in sliding engagement with 5 said primary sleeve, said sleeves and said heads defining a chamber; and means for supplying a fluid to said chamber.

13. In a deep-well pump, the combination of: a pump section; a pump shaft in said 10 pump section; an impeller secured to said pump shaft in said pump section; a piston structure operatively connected to said pump shaft; and walls rotating with said pump shaft and forming a chamber in which said 15 piston structure may slide in engagement with said walls, said chamber being in communication with the fluid pumped by said pump section in a manner to exert an upward force on said piston structure.

14. In a deep-well pump, the combination of: a piston structure; a cylinder structure relative to which said piston structure may slide to vary the volume of a chamber in said cylinder structure; means for simultaneously 25 rotating said structure; a pump shaft connected to one of said structures in a manner to slide this structure relative to the other of said structures as a function of the position of said pump shafts; and means operatively connected to said pump shaft for building up a high fluid pressure in said chamber. 95

15. A combination as defined in claim 14 in which a small leakage takes place between 35 said piston structure and said cylinder structure tending to lower the pressure in said chamber, and including valve means controlled by the position of said pump shaft for replenishing the supply of fluid in said 40 chamber. 100

16. In a deep-well turbine pump, the combination of: a pump unit positioned in a well; a rotor in said pump unit and including a pump shaft; a line shaft extending upward 45 through said well; variable-volume means operatively connected to each of said shafts for controlling the relative axial positions of said shafts and transmitting a thrust therebetween; and means for supplying fluid 50 pumped by said rotor to said variable-volume means. 105

17. In a deep-well turbine pump, the combination of: a pump unit positioned in a 55 well; a rotor in said pump unit and including a pump shaft; a line shaft extending upward through said well; variable-volume means operatively connected to said shafts for controlling the relative axial positions 60 of said shafts, said variable-volume means being in communication with the fluid being pumped by said rotor and pulling upward on said pump shaft and pulling downward on said line shaft; and valve means controlled by the position of said pump shaft 65 110

for controlling the pressure of said fluid in said variable-volume means.

In testimony whereof, I have hereunto set my hand at Los Angeles, California, this 24th day of February, 1928. 70
